BOXING GAME

Fernando Tintorer, Prov de Matz, Cuba
(Calle Maceo 5, Perico, Matanzas, Cuba)

Filed Sept. 26, 1957, Ser. No. 686,527

1 Claim. (Cl. 273—136)

This invention relates to an amusement device or game, and more particularly to a game for simulating a boxing match or prize fight.

The object of the invention is to provide a game which is adapted to be used for simulating a boxing match or prize fight, and wherein there is provided a housing which has posts and ropes connected thereto which are adapted to be arranged in such a manner as to represent a boxing ring, and wherein there is provided dice which are adapted to be rolled whereby the players will be able to play the game according to the rules established.

Another object of the invention is to provide a boxing game which includes a hollow housing that is adapted to be used for holding the various parts such as the dice when the game is not being used, and wherein the housing serves as a means for providing a compact storage area for the various parts of the game so that the game will occupy a minimum amount of space for storage or shipment.

A further object of the invention is to provide a boxing game which is extremely simple and inexpensive to manufacture.

Other objects and advantages will be apparent during the course of the following description.

In the accompanying drawings, forming a part of this application, and in which like numerals are used to designate like parts throughout the same.

Figure 1 is a perspective view showing the device set up ready to be used when players are playing the boxing game.

Figure 2 is a sectional view taken on the line 2—2 of Figure 1.

Figure 3 is a sectional view taken on the line 3—3 of Figure 2.

Figure 4 is a plan view illustrating the flap and showing the flap removed from the housing.

Figure 5 is a plan view of one of the bases showing the indicia or printed matter thereon.

Figures 6 through 11 are perspective views illustrating the dice which are adapted to be used when playing the game.

Referring in detail to the drawings, there is shown an amusement device or game which simulates a boxing match or prize fight when it is being used, and the game includes a hollow housing which is indicated generally by the numeral 10. The housing 10 has its interior hollow as at 11, and the housing 10 is constituted by spaced parallel vertically disposed end walls 12 and spaced parallel vertically disposed side walls 13. A wall member 14 closes one end of the housing 10, while the other end of the housing 10 is open as at 15.

The end walls 12 are provided with slots, and slidably mounted in the slots 16 are bases or plates 17. The bases 17 are provided with indicia or printed matter 18 thereon, as for example, as shown in Figure 5. Secured to the outer end of each of the bases 17 is a vertically disposed end piece 19, and projecting outwardly from each end piece 19 is a finger piece 20, and the finger piece

2

20 can be used for moving the bases 17 through the slots 16.

There is further provided a pair of similar flaps which are each indicated generally by the numeral 21, and the flaps 21 are adapted to be hingedly connected to the end walls 12 by means of hinges 22, Figure 4. A transparent window or viewing device 23 is carried by each flap 21, and the viewing devices or windows 23 permit the players or users to readily observe the indicia 18 on the bases 17.

There is further provided corner braces 24, and extending upwardly from the housing 10 and removably connected thereto is a plurality of spaced parallel vertically disposed posts 25 which have ropes 26 connected thereto by means of securing elements 27.

In Figures 6 through 11, the numerals 28, 29, 30, 31, 32, and 33 indicate dice which are adapted to be used when playing the boxing game of the present invention.

From the foregoing, it is apparent that there has been provided an amusement device or game which, when being played, will simulate a boxing match or prize fight. In use, the dice such as the dice 28 through 33 shown in Figures 6 through 11 may be rolled, and these dice can be rolled on the upper surface of the wall member 14

as for example when the parts are in the position shown in Figures 1 and 2. These dice may be used in accordance with established rules of playing the game so that for example, the indicia 18 on the bases 17 may be used to provide scoring for the various players. The bases

17 can be moved in or out of the slots 16 by gripping the finger pieces 20, and the flaps 21 have the transparent windows 23 therein so that the players can readily observe the indicia 18 through the windows 23. As previously stated, the interior of the housing 10 is hollow

as at 11 so that when the device is not being used, the bases 17 can be moved outwardly whereby the posts 25 and ropes 26 can be disconnected from the housing and these members as well as the dice of Figures 6 through 11 can be conveniently stored or placed in the hollow interior 11 of the housing 10. Then, the bases 17 can be moved to their inner or closed position so that the material within the interior of the housing 10 will not accidentally fall out. When the bases 17 are moved to their closed position, the flaps 21 can be swung up or pivoted up so that they occupy a position which is contiguous to the end walls 12.

The parts can be made of any suitable material and in different shapes or sizes. As previously stated, the players may play the game with suitable rules or instructions and the ring-like housing is adapted to be positioned between the two persons who play the game, and suitable note books or other scoring sheets can be used with the game. The rules may take into consideration various factors which simulate an actual boxing match such as medical opinions, fighters of different weights, and the dice may be cast alternately by the players. The ring converts into a container for holding the various parts when the game is not being played. Suitable rules or instructions can be set up so that various events such as jabbing, knock outs, as well as such things as stopping the fight when a player is hurt, can be incorporated in the rules of playing the game. Also, suitable provision may be made for the number of rounds as well as the duration of the rounds, and knock outs may also be provided for.

The ring may be formed by the rectangular box or housing 10, and openings are provided in the ends of the box or housing 10 for releasably holding the posts 25, and the posts 25 provide supporting means for the ropes 26. When the game is not being played, the box can be turned upside-down so that the parts can be inserted through the opening 15 into the interior 11. The win-

dows 23 permit the players to observe the scoring or indicia 18 on the bases 17, and the flaps 21 may also have indicia thereon as for example as shown in Figure 4. Other means can be provided for connecting the flaps 21 to the end walls 12, besides the hinges 22, and if desired, these flaps 21 can be entirely removed when desired.

I claim:

A game board comprising a hollow housing provided with a hollow interior, said housing embodying a pair of spaced parallel vertically disposed end walls, and spaced parallel vertically disposed side walls, said housing further including a horizontally disposed upper wall member, the bottom of the housing being open, there being slots in said end walls, a base slidably mounted in each slot, said bases having indicia thereon, a vertically disposed end piece secured to the outer end of each of said bases, a finger piece extending outwardly from each end piece, a flap hingedly connected to each of said end walls, and a transparent window carried by each flap, said bases being capable of movement into and out of extended and

retracted positions through said slots, and whereby when the bases are moved to their retracted closed position, the flaps occupy a position which is contiguous to the end walls, and wherein when the bases are in their extended position, the flaps overlie the bases so that the indicia on the bases can be viewed through the transparent windows of the flaps.
